CLAIM

The ornamental design for a medical X-ray imaging machine, as shown and described.

DESCRIPTION

FIG. 1 is a perspective view of a medical X-ray imaging machine showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is another perspective view thereof with the supporting post rotated; and,
FIG. 9 is another perspective view thereof with the supporting post rotated and elongated.
